UNITED STATES PATENT OFFICE.

CURTIS B. CAMP, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

SIGNALING DEVICE.

1,134,256.

Specification of Letters Patent.

Patented Apr. 6, 1915.

Application filed April 15, 1912. Serial No. 690,972.

To all whom it may concern:

Be it known that I, CURTIS B. CAMP, a citizen of the United States, and resident of Chicago, county of Cook, and State of Illinois, have invented certain new and useful Improvements in Signaling Devices, of which the following is a specification.

My invention has to do with signaling devices and particularly to devices such as are used for giving calling or warning signals, an object being to provide improved and simplified operating and controlling means therefor.

My invention relates more particularly to devices of the character referred to in which air pressure is used for operating the sound producing device such as a wind horn.

In devices of the character described where used on automobiles, motor boats or like conveyances a large bulb is usually provided to supply the air current for operating the device, but there are certain disadvantages in the use of such a bulb due to its comparatively large size and inconvenience of manipulation. Furthermore, devices of this character are usually capable of producing but a single sound or tone which it is apparent may not suit the various occasions in which such a warning signal is to be employed.

In the present invention I provide simple means for controlling such a device to secure various degrees of actuation thereof. For a better understanding of my invention reference may be had to the accompanying drawing in which—

Figure 1 illustrates diagrammatically an application of my invention and Fig. 2 illustrates a detailed construction of a valve device for controlling the passage of air through the horn.

In practising my invention I preferably provide a horn or bell 1 connected to a source of air 2, by the conducting tubes 3—4—5. The air pressure may be supplied by any means, but I preferably connect a chamber 2 to a pump 6 through the medium of a conducting pipe 7 having a check valve 8 interposed. The pump 6 may be operated in any desirable manner and I have shown it connected to the shaft 9 of an automobile engine, although it is apparent that the source of power for operating pump 6 may be any desired source. A puppet valve 10 is provided to allow the escape of air should

the pressure exceed a predetermined amount, or any of the well known regulating means to prevent excessive pressure in air chamber 2 may be employed. I have shown means for maintaining substantially a constant pressure in air chamber 2 comprising preferably a piston 12 and spring 13 so adjusted that the pressure in tank 2 remains substantially constant as will be apparent.

For sound producing devices I preferably employ a pair of reeds 14—15 constructed in a well known manner and adapted to produce a sound through bell or horn 1 when the air pressure is relieved by the opening of valves 16—17 respectively. To control said valves 16—17 I provide electromagnets 18—19 having armatures 20—21 respectively and operatively connected with said valves 16—17 respectively, two types of magnets on the one signaling device being shown for the sake of convenience and simplification. Any source of current may be used for operating these magnets and I have shown a battery 22 connected in circuit with said magnets and controlling keys 23—24. Magnet 19 is so arranged that when an energizing circuit is closed through its winding it maintains its armature 21 attracted and valve 17 opened, while magnet 18 is so arranged that it will automatically vibrate its armature, this being brought about by means of the interrupter contacts 20' which open each time magnet 18 is energized. In other words when a direct current circuit is closed through magnet 18, due to the interrupter 20' it will automatically vibrate its armature in a well known manner, thus operating valve 16 and causing an intermittent operation of reed 14.

Although I have chosen to illustrate my invention with two different operating types of magnets 18—19, I contemplate using various combinations thereof and as is apparent will readily suggest themselves.

For controlling the magnets 18—19, keys 23—24 are provided, each key being adapted for different control of the magnets and causing a variable operation of the signaling horn. For instance with key 23 depressed to close contacts 25 and 26, magnet 19 is energized to open valve 17 and allow the operation of reed 15 thereby producing a certain tone through bell or horn 1, and as key 23 is further depressed contact 27 is engaged thereby also cutting magnet 18 in 110

circuit to open valve 16 and allow the operation of reed 14, thereby producing a different tone in horn 1 as I preferably arrange the two reeds to chord. It is apparent that 5 either one or the other of said magnets may be cut out of circuit by means of switches 28-29 so that a single tone may be produced if desired.

Now by means of switch 24 a different 10 operation of the horn will be secured as will be apparent from the following. For instance if key 24 is depressed to close contact springs 30-31 but not far enough to interrupt normal contact 31, a circuit through 15 magnet 19 is closed, causing an operation of reed 15 and producing a distinctive tone, and upon further depression of key 24, normal contact 31 is interrupted and contacts 30, 31, 32 are closed, thereby cutting magnet 20 19 out of circuit and magnet 18 into circuit causing its operation and producing a second distinctive sound from horn 1. While I have illustrated two ways of connecting 25 keys in circuit, it is apparent various other methods of connecting the controlling keys in circuit will readily suggest themselves.

In Fig. 2 I have illustrated a construction 30 of mechanism valve 16-17, having preferably illustrated the valve 16 and its controlling mechanism and using like reference characters to indicate like parts. Electromagnet 18 which comprises preferably a pair of magnet spools is constructed to cause 35 a comparatively slow operation of armature and to this end I provide copper sleeves 33 for the cores of the electromagnets, thereby causing the magnet to retain its armature for a short period after the circuit through 40 its winding is interrupted.

Although I have disclosed certain applications 45 of my invention it is apparent that many changes and modifications thereof may be made, also various ways of connecting the magnets and controlling keys in circuit will be apparent, and therefore I do not desire to be limited to the exact structure as disclosed but aim to cover all those changes and modifications as come within the spirit and scope of the appended claims.

What I claim as new and desire to secure 50 by United States Letters Patent is:

1. In a signaling device of the class described the combination with a sound pro-

ducing wind horn, of air ducts and a source 55 of air pressure connected therewith, electromagnetic controlling means for each of said air ducts, and a manually operable switching lever and suitable connections for operating one or both of said electromagnetic controlling means to produce different 60 sounds from said horn.

2. In a signaling device of the class described the combination with a sound producing wind horn, of air ducts and a source 65 of air pressure connected therewith, electromagnetic controlling means for each of said air ducts, a manually operable switching lever having different degrees of actuation and suitable connections whereby one or more of said electromagnetic controlling 70 means are operated and whereby different sounds may be produced by said horn.

3. In a signaling device of the class described, the combination with a sound producing wind horn, of air ducts and a source 75 of air pressure connected therewith, a valve in each of said ducts, electromagnetic controlling means for each of said valves, a manually operable switching lever having 80 different degrees of actuation whereby one or more of said electromagnetic controlling means are operated and whereby different sounds may be produced by said horn.

4. In a signaling device of the class described, the combination with a sound producing wind horn, of air ducts and a source 85 of air pressure connected therewith, a valve in each of said ducts, electromagnetic controlling means for each of said valves, a manually operable switching lever having 90 different operating positions and suitable connections whereby when said lever is in one position one of said electromagnetic controlling means is operated and when said lever is moved to another of its operating 95 positions another of said electromagnetic controlling means is operated, each of said controlling means being adapted to produce a different sound by said horn.

Signed by me at Chicago, county of Cook 100 and State of Illinois, in the presence of two witnesses.

CURTIS B. CAMP.
